PLAYER ACTION COMPANY, OF WORCESTER, MASSACHUSETTS, A CORPORATION
OF MASSACHUSETTS.

ACCENTING DEVICE FOR MUSIC-PLAYERS.

1,011,567.

Specification of Letters Patent. Patented Dec. 12, 1911.

Application filed June 19, 1909. Serial No. 503,127.

To all whom it may concern:

Be it known that I, THEODORE P. BROWN, a citizen of the United States, residing at Worcester, in the county of Worcester and 5 State of Massachusetts, have invented a new and useful Accenting Device for Music-Players, of which the following is a specification.

A common arrangement in automatic 10 music players is to connect a vacuum inducing apparatus, such as the ordinary feeders, through a spring-pressed reservoir or receiver to the set of striking pneumatics so that the action of the vacuum inducing de- 15 vice is regulated and evened by the receiver. Players have also been provided with another or second passage between the vacuum inducing apparatus and the set of striking pneumatics, which second passage is con- 20 trolled by a valve which is normally closed and which can be opened by a hand lever or by a pneumatic controlled from a sup- 25 plemental opening in the tracker-bar when it is desired to connect the vacuum inducing apparatus directly with the wind-chest for playing notes louder or accenting the same. In these arrangements the supplemental perforations in the music sheet al- 30 ways come in substantial transverse line with the perforations for the notes which are to be accented. In all these devices with which I am familiar the auxiliary reservoir or receiver always remains in communica- 35 tion with the vacuum inducing device even when the latter is directly connected to the set of striking pneumatics. This has the dis- 40 advantage that although the keys of the notes to be accented can be struck directly from the vacuum inducing apparatus, the effect is modified by the receiver, so that it is not easy to obtain a sharp or clear cut accent. Another disadvantage of this old ar- 45 rangement is that when the ordinary playing is being done through the receiver or auxiliary reservoir the same is colorless and cannot be quickly regulated and controlled by the vacuum inducing apparatus. To 50 overcome these disadvantages I have simplified and rearranged the parts in the following new combinations.

In my improved device the vacuum inducing apparatus communicates by a direct passage at all times with the striking

pneumatics, the receiver or reservoir is ar- 55 ranged to have communication into said di- rect passage, and the connection between the receiver and the direct passage is con- trolled by a valve which is normally open for the usual or soft playing, and is closed for accenting. This enables me to obtain 60 very marked effects.

In playing the ordinary accompaniments or soft notes the playing is directly under the control of the vacuum inducing apparatus, although the reservoir tends to regu- 65 late the pressure. Moreover when the aux- iliary reservoir or receiver is cut off the accenting can be made very sharp and clean cut with any desired degree of loudness as 70 the notes are then directly under the con- trol of the vacuum inducing apparatus, and there is no auxiliary reservoir or other parts to drag and hold back the accenting.

The valve controlling the communication 75 between the auxiliary reservoir and the di- rect passage between the vacuum inducing apparatus and the set of striking pneumatics may be controlled by hand or may be controlled by a pneumatic operated from supplemental perforations in the music 80 sheet. In this arrangement the supple- mental perforations in the music sheet come substantially in transverse line with the per- 85 forations for the notes which are not to be selected or accented, so that in ordinary playing the valve will be held open. When a note or notes is to be accented the supple- 90 mental perforation is discontinued which causes the pneumatic to shift the valve, thus giving direct connection between the vacu- 95 um inducing apparatus and set of pneumatics and cutting off the auxiliary reservoir or storor, no matter what its position happens to be.

It does not follow as a matter of course that 95 the selected notes necessarily will be played loud or accented. They may all of them be played soft, as the complete control of the se- 100 lected notes is given to the operator, and he can play the same with any force desired. But usually the selected notes are accented, be- cause in playing the melody it is usually a case of playing one or usually at the most three notes at a time which does not necessi- 105 tate a large amount of wind, whereas the playing of the accompaniment usually does

require a large quantity of wind, as there are often a great many notes struck at one time. Therefore the equalizer or reservoir is very desirable for use in connection with the accompaniment.

5 In practice the supplemental perforations in the music sheet are made to commence slightly in advance of the leading ends of the perforations for the notes not to be selected or accented, so that the time of 10 the operation of the pneumatic valve can be regulated.

When one or more notes of a chord is or are to be selected or accented, the leading 15 ends of the perforations for the notes not to be selected or accented are advanced beyond the leading ends of the perforations for the notes to be selected or accented and the supplemental perforations in the music sheet 20 are arranged to end between the leading ends of the perforations for the notes not to be selected or accented and the leading ends of the perforations for the notes to be selected or accented, and preferably slightly before 25 the leading ends of the perforations for the notes to be selected or accented. In this way the notes of the chord not to be accented will start in operation first under the action of the reservoir, the valve will close, the notes 30 to be accented will be brought into operation, and as they work under higher pressure will overtake the notes which are not to be accented, and the result will be a chord struck with the notes to be accented being 35 given a heavier blow.

In some cases the note to be selected or accented can be arranged slightly in advance of the accompaniment notes which form a chord therewith to give a peculiar effect.

40 One form of apparatus for practicing my invention is illustrated in the accompanying three sheets of drawings, in which—

Figure 1 is a sectional elevation of the apparatus with a diagrammatic representation 45 of a music sheet and tracker-bar connected therewith; Fig. 2 is a sectional view through the wind sheet showing the striking pneumatics, and Fig. 3 is a front elevation.

Referring to the drawings and in detail 50 A—A designate a pair of feeders which may be operated by pedals in the usual manner, and which feeders form the vacuum inducing apparatus. The feeders or vacuum inducing apparatus connect through openings 55 10 with a wind trunk B, which latter connects by pipe P with the wind chest C which contains or operates the set of striking pneumatics controlled by primary and secondary valves E and F as shown in Fig. 2, which 60 may be arranged in any of the ordinary ways. It will be seen by this arrangement that there is a direct passage between the vacuum inducing apparatus and the set of striking pneumatics consisting of the holes 65 10—10, wind-trunk B and pipe P.

An auxiliary reservoir or receiver B is arranged on the back of the wind trunk and is provided with a spring S tending normally to open the same. This auxiliary reservoir communicates by one or more passages 70 11 with the direct passage between the vacuum inducing apparatus and the wind chest. As shown, one passage 11 is controlled by a valve 12 which may be operated by suitable connections 13 from a hand lever 14, the hand lever 14 being shifted to close the valve 12 when it is desired to select or accent. Preferably, however, the selecting or accenting is automatically done from the music sheet. For this purpose one 80 of the passages 11 is controlled by a valve 15 which is operated by a link 16 connected to the movable wall of a pneumatic 17. A valve box 18 is arranged on top of the wind trunk. This valve box has a valve 19 operated by a diaphragm 20 and is provided with the usual bleeder passage 200. A passage 21 is arranged between the wind-trunk B and the space above the diaphragm 20. The valve 19 works in a space having a communication 22 with the atmosphere, and a communication 23 with the pneumatic 17. A pipe 24 communicates with the space under the diaphragm 20 and also with a supplemental opening D in the tracker-bar T, which 95 has the usual openings H for controlling the striking pneumatics.

N designates the note sheet. The same is provided with perforations for the notes not to be selected or accented, which perforations 100 are not lettered, and also with perforations for the notes to be selected or accented which are marked X. Said note sheet is also provided with supplemental perforations Y controlling the supplemental opening D. The 105 note sheet is wound back and forth between the usual rolls or spools so as to pass from the spool L to the spool M for playing in the usual manner. It will be noticed that the supplemental perforations in the note 110 sheet come substantially in transverse line with the perforations for the notes not to be selected or accented, and that when the notes to be selected or accented come over the note openings in the tracker the supplemental 115 opening D is covered. It also will be noticed that the supplemental perforations Y are arranged to commence slightly in advance of the leading ends of the perforations for the notes not to be selected or accented, so that the valve 15 will be fully opened and the reservoir R in operation at the time the leading ends of the perforations for the notes not to be selected or accented come into operation. It will also be noticed that the supplemental perforations Y end slightly in advance of the leading ends of the perforations X for the notes to be selected or accented, so that the valve 15 will be closed 120 and the reservoir cut off from the direct pas- 130

sage between the vacuum inducing apparatus and the striking pneumatics at the instant the note or notes to be selected or accented, comes or come into operation.

5 In case a chord is to be played in which one or more notes thereof is or are to be accented or selected as compared with the others, the same are arranged as shown at the transverse line V, that is, the leading 10 ends of the perforations for the notes not to be selected or accented are arranged slightly in advance of the leading end or ends of the note or notes to be selected or accented, and the supplemental perforation 15 in the music sheet ends between the leading ends of the perforations for the notes not to be selected or accented and the leading ends of the perforations for the notes to be selected or accented, and preferably slightly 20 before the leading ends of the perforations for the notes to be selected or accented. With this arrangement the three notes shown 25 on the transverse line V will be struck with the reservoir in operation, the perforation Y will end, the valve 15 will be closed, and at the time the note X comes into operation there will be a direct communication between the vacuum inducing apparatus and the wind chest, without the reservoir R. By 30 this arrangement not only will the note or notes X be selected, but the force with which the same is distinguished may be readily controlled by the operator, as the operator for selecting or accenting has each note directly 35 under the control of the vacuum inducing apparatus without the neutralizing effect of the reservoir. It also will be noticed that on the transverse line W an accented note X is arranged slightly in advance of three accompaniment notes. This 40 arrangement may be used when it is desired to accent or individualize particularly a note or notes of a chord, the slight interval of time in which the accented note or notes 45 comes into operation before the accompaniment notes, giving for some compositions the desired effect of particularly emphasizing or accenting a certain note or notes of a chord. Also as before pointed out, the 50 playing of the accompanying notes can be regulated as the air does not go through the auxiliary reservoir, the auxiliary reservoir simply acting as a storer to give smooth playing.

55 When the automatic valve 15 is employed in connection with the heretofore peculiarly arranged music sheet, the valve 12 is kept closed. The valve 15 when in operation is normally open. It is shown in Fig. 1 in the 60 position it assumes when a note is to be selected or accented. It will be noticed that not only can the selected note be accented, but if it is desired it can be played lighter or with any degree of loudness, as when the 65 same comes into operation it is directly un-

der the control of the vacuum inducing apparatus. Thus extremely artistic effects can be obtained.

When the music is put in the apparatus which does not have the supplemental perforations Y, the valve 15 will be closed, and the selecting or accenting can then be done by the hand controlled valve 12.

The details and arrangements herein shown and described may be greatly varied 75 by a skilled mechanic without departing from the scope of the invention as expressed in the claims.

Having thus fully described my invention, what I claim and desire to secure by Letters 80 Patent of the United States is:—

1. In an automatic musical instrument, the combination of a vacuum inducing apparatus, a set of striking pneumatics, a storage reservoir for regulating the pressure between the vacuum inducing apparatus and the striking pneumatics, a normally open valve controlling the action of the reservoir, and adapted to cut the reservoir off without stopping the connection between the vacuum 85 inducing apparatus and the striking pneumatics, a pneumatic controlling the valve, an opening in the tracker-bar for controlling the pneumatic, and a music sheet having supplemental perforations for controlling said opening substantially in transverse line with the perforations for the notes not to be selected or accented.

2. In an automatic musical instrument, the combination of a vacuum inducing apparatus, a set of striking pneumatics, a direct passage between the vacuum inducing apparatus and the set of striking pneumatics, a storage reservoir having communication into said passage, a valve for connecting or cutting off the reservoir from said direct passage, said passage being unaffected by said valve, a pneumatic for operating said valve, a supplemental opening in the tracker, and a music sheet having supplemental perforations for controlling said opening substantially in transverse line with the notes not to be selected or accented, the supplemental perforations therein commencing slightly in advance of the leading ends of 110 the perforations for the notes not to be selected or accented.

3. In an automatic musical instrument, the combination of a vacuum inducing apparatus, a set of striking pneumatics, a direct 120 passage between the vacuum inducing apparatus and said set of striking pneumatics, a storage reservoir having communication into said passage, a valve for connecting or cutting off the reservoir from said direct 125 passage, said passage being normally open and independent of said valve, a pneumatic for operating said valve, a supplemental opening in the tracker, and a music sheet having supplemental perforations for con- 130

trelling said opening substantially in transverse line with the notes not to be selected or accented, the supplemental perforations ending slightly in advance of the leading ends of the notes to be selected or accented.

4. In an automatic musical instrument, the combination of a vacuum inducing apparatus, a set of striking pneumatics, a direct passage between the vacuum inducing apparatus and said set of striking pneumatics, a storage reservoir having communication into said passage, a valve for connecting or cutting off the reservoir from said direct passage, a pneumatic for operating said valve, a supplemental opening in the tracker, and a music sheet having supplemental perforations for controlling said opening substantially in transverse line with the notes not to be selected or accented, the supplemental openings therein commencing slightly in advance of the leading ends of the perforations of the notes not to be selected or accented, and ending slightly in advance of the leading ends of the perforations for the notes to be selected or accented.

5. In an automatic musical instrument, the combination of a vacuum inducing apparatus, a set of striking pneumatics, a direct passage between the vacuum inducing apparatus and set of striking pneumatics, a storage reservoir having communication into said passage, a valve for connecting or cutting off the reservoir from said direct passage, a pneumatic for operating said valve, a supplemental opening in the tracker, a music sheet having supplemental perforations for controlling said opening substantially in transverse line with the notes not to be selected or accented, the perforations in the music sheet for the notes not to be selected or accented being slightly in advance of the leading ends of the perfora-

tions for the notes to be selected or accented, and supplemental perforations in the music sheet ending between the leading ends of the 45 perforations for the notes not to be selected or accented and the leading ends of the perforations for the notes to be selected or accented.

6. In an automatic musical instrument, 50 the combination of a vacuum inducing apparatus, a set of striking pneumatics, a direct passage between the vacuum inducing apparatus and said set of striking pneumatics, a storage reservoir having communication 55 into said passage, a valve for connecting or cutting off the reservoir from said direct passage, a pneumatic for operating said valve, a supplemental opening in the tracker, a music sheet having supplemental perforations for controlling said opening substantially in transverse line with the notes not to be selected or accented, the leading ends of the perforations for the notes not to be selected or accented being slightly in advance 60 of the leading ends of the perforations for the notes to be selected or accented, and supplemental perforations in the music sheet between the leading ends of the perforations for the notes not to be selected or accented 70 and the leading ends of the perforations for the notes to be selected or accented, the supplemental perforations ending slightly after the leading ends of the perforations not to be selected or accented and slightly before 75 the leading ends of the perforations for the notes to be selected or accented.

In testimony whereof I have hereunto set my hand, in the presence of two subscribing witnesses.

THEODORE P. BROWN.
